J. F. LAMB.

INTERLOCK FOR SWINGING POWER DRIVEN WRINGERS.

APPLICATION FILED OCT. 4, 1920.

1,378,472.

Patented May 17, 1921.

UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

INTERLOCK FOR SWINGING POWER-DRIVEN WRINGERS.

1,378,472.

Specification of Letters Patent.

Patented May 17, 1921.

Application filed October 4, 1920. Serial No. 414,612.

To all whom it may concern:

Be it known that I, JOSEPH F. LAMB, a citizen of the United States, residing at New Britain, county of Hartford, State of Connecticut, have invented a certain new and useful Improvement in Interlocks for Swinging Power-Driven Wringers, of which the following is a full, clear, and exact description.

- 10 This invention relates to an interlock for a swinging power-driven wringer and has for its object to provide a wringer of that type in which the reversing mechanism swings with the wringer into any one of a plurality of positions with a locking lever carrying a detent, said lever interlocking with the handle of the reversing mechanism so that when the motor is driving the wringer in either direction the detent cannot be withdrawn so as to permit the wringer to be swung, and when the detent lever is actuated so as to permit the wringer to be swung, the motor cannot be operatively connected to the wringer.
- 15 20 25
- 20 The following is a description of an embodiment of the invention, reference being had to the accompanying drawings, in which—

Figure 1 shows in side elevation a portion of the wringer mounted upon a washing machine;

Fig. 2 is an end elevation of the same;

Fig. 3 is a detail view of the casing containing the reversing mechanism showing the reversing handle in position for driving the wringer in one direction in full lines and in dotted lines in neutral position and in position for driving the wringer in the opposite direction; and

40 Fig. 4 is a detail of the detent lever.

Referring more particularly to the drawings, 1 is a wringer secured to an arm 2, which is integral with the body portion 3 of a swinging wringer support. The lower part of this body portion 3 is formed so as to fit closely upon a sleeve 4 secured to and projecting from a base plate or standard 5. Within the sleeve 4 is a bushing 6 carried by the upper end of a power-driven shaft 7.

45 50 55

14 is the handle of the reversing mechanism connected to the shaft 15. This handle is provided with a spring-pressed pawl detent 17, which engages a recess 18 in the casing containing the reversing gears, this recess 18 being directly above the shaft 15

so as to be engaged by the pawl detent when the handle 14 is in vertical position. The shaft 15 carries an eccentric pin 19, which turns in a rectangular block 20, located between the shoulders of a clutch member 21 mounted upon a shaft 22 with a spline so as to rotate therewith. Loosely mounted on this shaft 22 are beveled gears 23 and 24 provided with clutch faces, with which the clutch faces of the clutch member 21 engage when the handle 14 is in either horizontal position but from which they are both free when the handle 14 is in the vertical position, as shown in Fig. 2.

As is well known to those who have operated power-driven swinging wringers, there is danger in unlocking the wringer when the power is on, particularly if any clothes are being wrung, since, if the power is on and the wringer is unlocked so as to be free to swing, the driving power will act to swing the wringer which may strike a person standing nearby a blow resulting in serious damage.

Ordinarily, the power is connected and disconnected from the wringer by the reversing mechanism which has a forward position, a rearward position and a neutral position. In the neutral position the power is disconnected from the wringer. This reversing mechanism is ordinarily located in the swinging support, which is connected with the wringer so as to be removable therewith, as a unit, from the washing machine.

To prevent the danger above referred to, it is only necessary to make the detent interlock with the reversing mechanism handle, so that the detent can be withdrawn only when the reversing mechanism is in neutral position and the reversal mechanism can be thrown so as to connect the power with the wringer only when the detent is in locking position. This can obviously be done in various ways, but I have devised a lever located in a particular place and operating in a particular way so as to not only be easy to operate but to have a simple interlocking relation.

In order to provide an easily operated interlocking detent, I have pivoted to the portion 3 at 8, directly below the shaft 15, a detent lever 9 having a thumb piece or handle 10 overlying the shaft 15 and the spring-pressed plunger 11, which tends to move the

handle outward, although permitting it to be moved into the position shown in dotted lines. The lower end of the detent lever 9 is provided with the finger 12, which fits in 5 any one of a plurality of recesses 13 in the base plate 5. Upon withdrawing the finger 9 from one recess by pressing the handle 10, the wringer is free to be swung to another position with the finger 12 opposite another 10 recess 13, so that the entry of the finger into the other recess will lock the wringer in the new position.

In order to relieve the pivot 8 and the lower arm of the lever 9 of strain, I have provided the portion 3 with two lugs 3', spaced apart so as to be in close engagement with the sides of the lever 9 adjacent to the finger 12. These projections constitute abutments which relieve the lever 9 from lateral strain and reduce the danger of breaking 20 or other damage.

In order to prevent the withdrawal of the finger 12 when the reversing mechanism is not in neutral position, I provide the reversing handle with a flange 25 having a notch 26, which is directly below the shaft 15 when the handle 14 is in vertical position and provide the lever 9 with a projection 26' which is adapted to enter the recess 26 when the 25 handle 14 is in vertical position, but which blocks the lever 9 from movement when the handle 14 is moved out of vertical position so as to carry a portion of the flange 25 into alignment with the vertical plane passing 30 through the shaft 15 and the projection 26'. 35

By this means is provided a readily ac-

cessible detent lever which can be actuated only when the reversing mechanism is in neutral position, and which can be actuated by a horizontal pressure.

It is to be noted that the lever 9, being pivoted to the portion 3, revolves therewith so that its handle 10 is always in a vertical plane passing through the axis of the shaft 15, and lies over the end of said shaft bringing the manually operated portions of the lever 9 and handle 14 in close relation to one another.

As will be evident to those skilled in the art, my invention permits of various modifications without departing from the spirit thereof or the scope of the appended claim.

What I claim is:

In a wringer, the combination of a power-driven shaft, a base-plate having a plurality 55 of recesses, a support mounted on said base-plate so as to rotate about the axis of said shaft, a wringer mechanism carried by said support, a reversing mechanism contained in said support and having an actuating shaft projecting horizontally therefrom, a handle mounted upon said actuating shaft, and provided with a notch, a lever mounted on said support in a vertical plane passing through the axis of said shaft, said lever having a finger on its lower end adapted to enter said recesses in the base-plate carrying said support and as to which base-plate said support is revoluble and being provided adjacent to its upper end with a projection 60 65 adapted to enter said notch.

JOSEPH F. LAMB.
